COMBINATION MAILING AND LETTER ENVELOPE

Filed March 24, 1924

Inventor:
Charles E. Porter, Jr.

UNITED STATES PATENT OFFICE.

CHARLES EDWIN PORTER, JR., OF ST. PAUL, MINNESOTA.

COMBINATION MAILING AND LETTER ENVELOPE.

Application filed March 24, 1924. Serial No. 701,424.

This invention relates to the process of making an envelope which will carry third or fourth class mail and first class mail in separate compartments under one cover, and 5 has for its object the making of an envelope which is stronger, more easily and more economically manufactured than other envelopes in its general classification.

The drawing, "Figure 1," shows the envelope after it has been cut from a single 10 sheet of paper. All portions marked "G" represent gumming. The dotted portion marked "W" represents a portion of the envelope which has been cut or died out.

15 In the making of this envelope, a single sheet of paper is first cut to conform to the figure shown in the drawing "Figure 1." The figure so cut is then gummed on all portions marked "G." The gumming is placed 20 on one side of the envelope only. The section "W" is then cut out, and the envelope is also cut along the two lines "7." The section "E" is then folded along the line "4" up and over the section "D" and glued in 25 place by the portions "G" on section "D." The portion thus folded is then folded along the line "5" up and over the section "C." The section "B" is then folded along the line "2" down and over the portion already 30 formed. It is glued in place by the portion marked "G" from the right edge of section "B" to the line on the right numbered "7" and from the left edge of section "B" to the line on the left numbered "7." The 35 flap or tongue "A" formed on the free edge of the flap "B" is then folded back and up along the line "1" and left free. The flap "H" is then folded along the line "6" to the right and over the body of the envelope 40 formed by the folding of sections "A," "B," "C" and "D," and glued in place by the gumming on that flap. The envelope being thus formed, third or fourth class mail may be inserted along the line "3" and the flap 45 "F" folded over and glued or fastened in place by any appropriate fastening device. First class mail may be inserted through the portion "W." The portion for first class mail is sealed by folding the flap "A" down 50 along the line "1" and gluing same along the gummed portion thereon.

I claim:

55 1. An envelope comprising, a main panel having a flap on one edge adapted to be folded thereon, said flap being formed with

a slot for a letter extending parallel to said fold, an integral extension adapted to be folded inwardly on said flap to form a small pocket in the envelope, a second flap on the opposite edge of said main panel adapted 60 to over-lap said first mentioned flap and arranged to complete a larger pocket, a shorter flap, formed on the free edge of said second flap, adapted to close said slot, and end portions on the main panel disposed to 65 overlap the ends of said flaps, one of said end portions being normally free to allow access to said larger pocket.

2. In an envelope, a main panel having a flap on one edge adapted to be folded thereon, said flap being formed with a slot for the insertion of a letter or the like extending parallel and adjacent to its edge remote from said main panel, an integral extension adapted to be folded inwardly on said flap 70 and normally arranged between said main panel and flap to constitute a partition in the envelope, a second flap on the opposite edge of said main panel adapted to over-lap said first mentioned flap, a tongue on said 75 second flap arranged to close said slot, and means for securing said flaps and extension in folded position.

3. An envelope consisting of a blank divided by folds into a main panel and flaps 85 on opposite sides of said panel, an extension on one of said flaps disposed to be folded between said flap and the main panel and constituting, when the envelope is in folded position, a partition between a large and 90 smaller pocket in the envelope, said flap being formed with a slot in spaced relation to the sides thereof, adapted to allow access to the smaller compartment, and a tongue on the opposite flap adapted to seal said 95 slot.

4. An envelope comprising a sheet divided by folds into a main panel and flaps on the sides of said panel, an integral extension on a normally outer flap disposed to be folded 100 between said flap and the main panel and constituting a partition between compartments in the envelope, said outer flap being formed with a slot in spaced relation to the sides thereof, and a tongue on another of 105 said flaps adapted to lie over said slot in unfolded continuation of the flap for sealing the slot.
